CLAIM

The ornamental design for a combined camera and image receptor, as shown and described.

DESCRIPTION

FIG. 1 is a right side elevational view of a combined camera and image receptor showing our new design, a left side view being a mirror-image thereof;

FIG. 2 is a rear elevational view thereof;

FIG. 3 is a front elevational view thereof;

FIG. 4 is a top plan view thereof;

FIG. 5 is a bottom plan view thereof;

FIG. 6 is a top, front and right side perspective view thereof; and,

FIG. 7 is a top, rear and right side perspective view thereof.

FIG. 1**FIG. 2****FIG. 3****FIG. 4****FIG. 5**

FIG. 6

FIG. 7
